UNITED STATES PATENT OFFICE.

EDWARD J. GILMORE, OF NEW YORK, N. Y.

GAME APPARATUS.

1,311,810.

Specification of Letters Patent. Patented July 29, 1919.

Application filed September 7, 1918. Serial No. 253,088.

To all whom it may concern:

Be it known that I, EDWARD J. GILMORE, a citizen of the United States, residing at New York, in the county of Kings and State 5 of New York, have invented certain new and useful Improvements in Game Apparatus, of which the following is a specification.

This invention relates to game apparatus and has as its object to provide an apparatus whereby a highly interesting and 10 amusing game may be played by two, three, or four players, the playing of the game requiring the exercise of judgment so as to be more or less of educational value.

15 In the accompanying drawings:

Figure 1 is a plan view of the game board of the invention;

Fig. 2 is a view illustrating in perspective several of the game pieces which are to be 20 moved by the players over the board.

The board is indicated in general by the reference numeral 1, and may be of wood, heavy card-board, metal, or of any other material suitable for the purpose and either 25 integral or made up of foldably connected sections. Also the board may be of any desired dimensions.

The playing area of the board is divided, except for its central portion, into a plurality of playing spaces which, while in the 30 drawings are in the form of squares, may assume any other desired outline. These spaces are indicated in general by the numeral 2 and may be defined by intersecting lines running parallel to the four edges of the playing field of the board or by broken lines as illustrated in the drawings, which broken lines intersect at 3 at the corners of the squares which they define. Certain of 35 the spaces constitute entrance spaces and are indicated by the numeral 4, and each of these entrance spaces is located at one edge of the playing field and midway between the ends of the said edge. In other words, there 40

45 is an entrance space at each of the four sides of the playing area. As stated above, the playing area is divided into the spaces 2, but at its central portion there is printed an objective or goal consisting of an inner

50 square 5 and an outer square 6 inclosing the inner square, the outer square having each of its sides interrupted as at 7 at a point midway between its ends to indicate an entrance to the goal. The entrances 7 to the 55 goal are each located opposite the entrance

space 4 at the respective side of the playing field.

The playing area is divided into four triangular players' fields by barriers, and each field is bounded by one edge of the board 60 having an entrance 4 at its midlength, and by two barriers converging to a goal entrance 7. To produce the barriers, certain of the spaces 2 on the diagonal lines between the corners of the goal square 6 and the corners of the playing field, are especially designated, as for example by circles 8, and these spaces constitute safety zones as will be presently explained. The other squares 2 along these diagonal lines are also especially designated by some arbitrary design 65 as for example a grille work, as indicated by the numeral 9, to indicate that they are barred zones. In the arrangement illustrated in the drawings, the space at each corner of the field constitutes one of the safety zones 8 and in the playing space preferably midway between this space and the corresponding corner of the goal square 6 also constitutes a safety zone, the remaining 70 spaces on the diagonal line being barred zones. The spaces at the opposite sides of each entrance space 4 may be also designated to constitute barred zones, so as to define the entrance. Thus each field is separated from 75 the fields next adjacent by two barriers, but each barrier has within its length two spaces 8 which may constitute gates unless closed as described below. If a gate is opened, the player may move out of his own field, but 80 also the next player may move in; hence the barrier may be destroyed as such by vacating a zone 8.

In connection with the board there are provided a number of game pieces preferably in the form of disks 10, several of which are illustrated in Fig. 2 of the drawings. There are preferably four sets of these game pieces, six in each set, those in each set bearing a distinctive color or design 95 differing from those in the other sets. Moreover, the game pieces of each set are severally numbered from 1 to 6 inclusive as indicated by the numeral 11.

The game piece designated by the ordinal 105 1 is to be known as captain, and the remaining game pieces of each set are known as men. The players take turns in throwing dice and move only the game piece the ordinal of which corresponds to the number 110

thrown. Thus if the number one is thrown the player throwing this number will place his captain game piece (designated by the ordinal 1) in the entrance space 4 at his 5 side of the board and on all succeeding throws of one this piece is moved one square. If two is thrown the number two piece is moved, by the player making the throw, two spaces; and so with the number 10 10 piece, number 4 piece, etc. The object of the game is to get any two pieces or the captain and one man belonging to the player into the goal square 5.

The game may be played by two, three or 15 four persons as previously explained, and when played by four any two players may play as partners against the other two. If the game is played by three, in order to equalize matters the two players adjacent 20 to the vacant space must each give up a game piece at the beginning of the game and lose their turn whenever the number of that piece is thrown by them.

The barred zones 9 cannot be occupied or 25 passed over at any time, and the game pieces occupying the safety zone spaces 8 cannot be captured. Game pieces, except the captains, are captured by having a game piece end its move on a playing space occupied 30 by an opponent's game piece of the same or of a higher number, and when captured the captured piece must be removed from the board. Thus a game piece bearing the ordinal 6 may be captured by any one of an 35 opponent's game pieces; a game piece bearing the ordinal 5 can be captured by any one of an opponent's except that bearing the ordinal 6, etc. The captains bearing the ordinal 1 cannot be captured. When making 40 a move a player is not permitted to pass over or jump an opponent's game piece although this is permissible with his own game pieces, and when partners are playing, either is permitted to pass over any of the 45 game pieces belonging to the other the same as over his own game pieces. Only the captain is permitted to enter the goal square from the side adjacent the player's starting space 4 and the other game pieces must enter 50 the goal square from one of the remaining three sides of the square. To enter the goal square, the move of any piece must corre-

spond in the number of spaces passed with the throw made, or, in other words, the last count of the throw must end in the goal 55 square. Players are permitted to make as many right angle turns as the count permits so that the game piece bearing the ordinal 6 may end its movement unless blocked, from either two or four squares from the 60 starting position. Thus this particular game piece may be moved into the goal square, if not blocked, when either two, four, or six playing spaces away from the goal square. If any game piece is so blocked 65 that it cannot be moved the full number of spaces indicated by the throw, the player loses his turn and must permit the game piece to remain where it is until he again throws that particular number and the move 70 of the game piece is not blocked. A player is not obliged to move his indicated game piece but may allow the same to remain if he sees fit to "pass" and forfeit his play.

Having thus described the invention, what 75 is claimed as new is:

1. A game board having a square checkered playing area, a goal at its center, four lines of checks radiating from said goal being specially designated and constituting 80 barriers dividing said area into four triangular players' fields, each having an entrance to said goal, and certain checks in said lines being specially designated differently from the others and constituting gates 85 in the barriers.

2. The herein described game comprising game pieces in four distinctive sets; and a board having its area checkered by playing spaces, certain spaces at the center of the 90 area being marked to constitute a goal having inlets at its four sides, diagonal rows of spaces from the goal to the edge of the area being specially designated as barred and constituting barriers dividing the area into four 95 individual players' fields, each having an entrance space opposite its respective goal inlet, and certain spaces in each of said rows being designated as safety zones and, when unoccupied, constituting gates through the 100 barriers, for the purpose set forth.

In testimony whereof I affix my signature.

EDWARD J. GILMORE. [L. S.]
